J. MATHEY,
STEAM VULCANIZER,
APPLICATION FILED AUG. 7, 1916.

Patented Mar. 6, 1917.

3 SHEETS—SHEET 3.

UNITED STATES PATENT OFFICE.

JOSEPH MATHEY, OF OMAHA, NEBRASKA.

STEAM-VULCANIZER.

1,218,101.

Specification of Letters Patent.

Patented Mar. 6, 1917.

Application filed August 7, 1916. Serial No. 113,639.

To all whom it may concern:

Be it known that I, JOSEPH MATHEY, a citizen of the United States, residing at Omaha, in the county of Douglas and State 5 of Nebraska, have invented certain new and useful Improvements in Steam-Vulcanizers, of which the following is a specification.

This invention relates to improvements in steam vulcanizers for use in repairing automobile tires or similar articles of rubber. 10

One of the objects of the invention is to provide a vulcanizer which may be used to advantage in mending both outer tires and inner rubber tubes, the same to consist of 15 few parts and of simple construction so that it may be used by any person of ordinary skill or experience for the purpose named.

Another object is the provision of an apparatus of this class which may be manufactured at slight expense, comparatively, and having its parts so arranged that heat 20 may be generated quickly and with the least expenditure of fuel.

A further object is to provide a vulcanizer 25 so arranged that all parts may be used at the same time, and when but one or more parts are to be used the steam may be shut off from the others.

Another object is to provide resilient 30 means whereby a pressure may be automatically maintained while the inner tubes are being vulcanized.

The apparatus includes, briefly, a flat vulcanizing platform, a boiler or casing and a 35 heating chamber all of which may be formed to advantage as a single metallic casting, certain contact-blocks being provided and so arranged that they may be suspended from swinging arms and moved above and de- 40 pressed upon the platform for the purpose of vulcanizing the rubber, and may be swung to an unobtrusive position when not in use. Also it includes a standard or frame for use in supporting the tubes while being vul- 45 canized, also certain tire molds provided with segmental chambers communicating with the boiler, and so arranged that the tires may be quickly secured or released, a safety valve, steam gage, and a gas pipe ar- 50 ranged for heating also being shown.

With the foregoing objects in view the invention presents a novel construction, combination and arrangement of parts as de-

scribed and claimed, and as illustrated in the drawings wherein,—

55

Figure 1 is a rear view in side elevation of a vulcanizer embodying my invention, a part being broken away and in section, a part of an automobile tire being added.

Fig. 2 is a bottom plan view of the vul- 60 canizer shown in Fig. 1, a part, midway between its ends being broken away, and the legs being omitted.

Fig. 3 is an end view of the vulcanizer. Fig. 4 is a vertical section on line 4—4 of Fig. 1 showing the steam chambers.

Figs. 5 and 6 respectively are plan and side views of a spring washer.

Fig. 7 is an enlarged vertical sectional view of a swinging arm member, the contact-block being in section, a part of an inner tube being added and in section. Fig. 8 is a side view illustrating the parts shown in Fig. 7.

Fig. 9 is a plan view of the apparatus, a 75 segment of an automobile tire being added and the tube hanger or standard being removed.

Fig. 10 is a side view of a tire form.

Fig. 11 is an end view of the tire form. 80

Fig. 12 is a side view of a tire-form or filler beading block.

Fig. 13 is an end view of the form shown in Fig. 12.

Fig. 14 is a side view of a compression 85 plate.

Fig. 15 is a broken away view showing a modified form for the bottom of the boiler, numerous pipes or vertical projections being substituted for the horizontal steam pipes. 90

Fig. 16 is a vertical sectional view on the line 16 16 of Fig. 15. Fig. 17 is a plan view of a sustaining-plate or brace bar.

Referring now to the drawing for a more particular description, numeral 1 indicates 95 a casing or container which may be constructed to advantage of a single metallic casting to provide upon its upper face a flat, elongated, rectangular, vulcanizing platform 2, a compartment 3 below and contiguous to 100 said platform for containing water, said casing having a longitudinal channel 4 below the compartment 3 formed by the two extensions 5, which project downwardly from the sides of the casing to form a heating cham- 105 ber.

Disposed parallel in the channel 4 and communicating with the boiler near the ends thereof are water pipes 6. Steam may be generated in the boiler, by use of gas or other suitable fuel, gas preferably being used in connection with a perforated pipe-burner 7 best shown in Fig. 1.

The boiler is provided with a steam gage 8, and a safety blow-out valve 9, by regulating which the certain steam pressure or heat best adapted for vulcanizing may be maintained. To facilitate the placing of water in the boiler a funnel 10 is attached thereto.

At 11 are indicated tire molds. They are formed of a single hollow metallic casting preferably of U-shape in cross-section permitting steam to circulate therein, and operating to distribute the heat uniformly. The steam is introduced from the boiler through pipes 13 and returned to the boiler through the connections 12, said members 12 and 13 being provided with cut-off valves to effect a saving of heat, when either or both of molds 11 are not in use with the other parts of the apparatus.

In order that the various sizes of tires may be repaired, the vulcanizer is provided with forms of various sizes and shapes to correspond to the standard sizes of tires. In operation, to vulcanize a tire 14, the channel or interior part of the tire is first filled with a "backing", such as coiled springs or the like (not shown). The metallic form 15 being in place within the mold, the tire is placed within the form, the pair of tire beading-forms 16 are then put in place and covered with a bearing-plate 17. A brace-bar 18 having a key bolt 19 threaded in the bar is then put in place and a required pressure applied to the tire by rotating the key-bolt. The bar 18 is provided with a recess *a* opening on one of its ends, and near its opposite end is provided with a recess *b* opening on one of its sides. The bar is secured upon the mold 11 by means of the pair of bolts 20 which traverse said recesses and are threaded in the upright sides of the tire mold. It is obvious that by varying the sizes and shapes of members 15 and 16 the several different sizes of tires may be vulcanized.

On one side of the vulcanizer platform and integral therewith are projections or lugs 33 more clearly shown in Figs. 7 and 8. These lugs are each formed with a vertical aperture to provide a bearing for the shank 28 of a curved arm 21. Threaded into the shank is a cap screw 22 serving as a keeper for the washers 23 and 23' said washers being interposed between the head of the cap-screw and the bottom of the lug. Between the washers 23 and 23' and encircling the shank of each arm is a spring washer 24 best shown in the enlarged detail Figs. 5

and 6. Washers 24 are preferably constructed of spring steel, each being incised to provide two free ends, and bent adjacent to its ends to extend outwardly of its sides as best shown in Fig. 6. This washer serves to create tension on the inner tube 25 (Figs. 7, 8,) while said tube is being vulcanized, thus accomplishing one of the objects of the invention.

To vulcanize an inner tube 25, it is placed between the platform and a plate 26, said plate being pressed downwardly by the key-bolt 27 which is threaded through a bushing at the upper end of arm 21. This pressure causes the arm 21 to move upwardly a limited distance and thereby compressing or flattening the spring washer 24. Since the rubber will expand from the action of heat during the operation of vulcanizing, the spring washer 24 will cause a pressure to be maintained upon the tube during said expansion without attention of the operator.

At 29 is indicated a supporting-frame or standard, its ends being thrust into sockets formed in the projections, this being useful for supporting the tubes while they are being vulcanized.

The brace bars 30 best shown in Figs. 3 and 4 operate to maintain the tire molds 11 in rigid relation with the casing. Legs 31 are preferably employed for supporting the casing, these being disposed in suitable sockets formed in the projections 32, said projections being a part of the casing.

Figs. 15 and 16 illustrate a modification in the arrangement of parts in the heating chamber, believed to be within the scope of the invention, comparatively short vertical pipes 34 being substituted for the horizontal pipes above described. The pipes 34 may be of any desired diameter and length their free ends being closed by caps 35, their upper ends projecting through the bottom of the boiler. These pipes may be arranged in rows or in staggered relation at the sides of the burner 7 as shown in Fig. 15. This arrangement facilitates heating and less fuel will be required.

Having fully described the several parts in detail, a further explanation relating to operation is not necessary.

What I claim as my invention and desire to secure by Letters Patent is,—

1. A vulcanizer, comprising, in combination with a casing having a flat top and provided on one of its sides with apertured projections and having a channel opening on its bottom, a perforated fuel pipe disposed in said channel, a plurality of pipes communicating with the container and disposed in said channel, curved arms each having a rectilinear part adapted to be moved vertically while disposed in an aperture of a projection and adapted to overhang the casing, a spring washer encircling the recti- 130

- linear part and normally resisting a vertical movement of a curved arm, a plurality of contact-plates above the casing, and a screw member carried by each curved arm for lowering or elevating the contact plates with reference to the top of the casing.
2. In a vulcanizer, a horizontally disposed, elongated casing rectangular in cross-section having a channel opening on its bottom and provided near its upper face with projections formed with vertical apertures, a perforated fuel pipe extending longitudinally of the casing within the channel, curved arms each having a rectilinear part adapted to be moved vertically while disposed in an aperture of a projection and adapted to have swinging movements to overhang the casing, keepers threaded in the rectilinear part of said arms, spring washers arranged for normally pressing the keepers outwardly of the projections of the receptacle for resisting the longitudinal movements of the rectilinear part of said curved arms, a plurality of contact-plates above the receptacle, means connected with the curved arms and contact plates for lowering or elevating said plates, a plurality of hollow molds substantially of U-shape in cross-section in communication with the water receptacle, a bearing-plate in each mold, a plurality of cross-bars each being removably mounted on a mold, and a plurality of screw-members, each being threaded in a cross-bar and engaging a bearing-plate for causing a vertical movement of said bearing-plate.
3. A vulcanizer comprising a metallic water container, means for heating the container, a plurality of curved arms each being resiliently mounted and adapted to have swinging movements to overhang the container, a plurality of contact-plates, and means connected with the curved arms and contact-plates for elevating or lowering said plates with reference to the container.
4. A vulcanizer comprising a metallic water receptacle rectangular in cross-section having a channel opening on its bottom and provided near its top with apertured projections, a perforated fuel pipe extending longitudinally of the receptacle within the channel, curved arms each having a rectilinear part adapted to be moved longitudinally while disposed in an aperture of a projection and adapted to have swinging movements to overhang the receptacle, keepers threaded in the rectilinear part of said arms, spring washers arranged for normally pressing the keepers outwardly of the projections of the receptacle for resisting the longitudinal movements of the rectilinear part of said curved arms, a plurality of contact-plates above the receptacle, means connected with the curved arms and contact plates for lowering or elevating said plates, a plurality of hollow molds substantially of U-shape in cross-section in communication with the water receptacle, a bearing-plate in each mold, a plurality of cross-bars each being removably mounted on a mold, and a plurality of screw-members, each being threaded in a cross-bar and engaging a bearing-plate for causing a vertical movement of said bearing-plate.

In testimony whereof, I have affixed my signature in presence of two witnesses.

JOSEPH MATHEY.
